UNITED STATES PATENT OFFICE

2,207,029

TYPOGRAPHICAL SLUG CASTING
MACHINE

Richard Henry Scott, Enfield, and William Fairall Gorse and Arthur Staniland Hayward, Altrincham, England, assignors to Linotype and Machinery Limited, London, England, a British limited-liability company

Application May 27, 1939, Serial No. 276,056
In Great Britain May 30, 1938

21 Claims. (Cl. 199—50)

This invention relates to typographical slug casting machines, such as those known commercially under the registered trade mark "Linotype," wherein composed lines of matrices and spacebands are sustained between a pair of line-clamping jaws in front of a slotted mould in which a typebar or slug is cast, and wherein after the casting operation, each line is removed from between the clamping jaws for delivery to a distributing mechanism, and the cast slug is ejected from the mould after the latter has been removed from the casting position to the ejecting position.

In such machines as usually constructed, the line clamping jaws are mounted in a vise frame which also carries other mechanisms, such as the elevator or line transporter and justifying and quadding devices, the operations of which are controlled by cams on a shaft at the rear of the machine through levers extending forwardly to connect with the respective mechanisms on the vise frame. Moreover, the vise frame is mounted to swing forwardly about a horizontal axis to give access to parts of the machine located behind it, which necessitates detachable connections between certain of the said mechanisms and levers.

The principal objects of the invention are to effect a simplification of the devices for operating the vise frame mechanisms, and to provide greater freedom of access to parts located at the rear of the vise frame. A further object of the invention is to adapt the vise frame for use with a mould which is movable to and from a horizontal ejecting position, so as to provide free passage for the ejection of a slug from the mould at the rear of the vise frame to a galley at the front thereof.

With these objects in view, the invention contemplates an arrangement in which the operating levers for the vise frame mechanisms are mounted so as to be movable with the vise frame and are controlled from a cam shaft which is co-axial with the pivot of the said frame. The invention further contemplates the arrangement of the respective mechanisms on the vise frame so as to leave a central portion thereof free from obstructions from front to rear.

One constructional form of apparatus according to the invention is illustrated, by way of example, in the accompanying drawings, in which:

Figure 1 is a front elevation of a vise frame and cam shaft according to the invention;

Figure 2 is a front elevation of the vise frame

and associated parts, drawn to a larger scale and partly broken away;

Figure 3 is a side elevation partly in section on the line 3—3 of Figure 2, as viewed from the right of that figure;

Figure 4 is a plan view, partly in section, taken on the line 4—4 of Figure 2, and

Figure 5 is a diagram indicating different settings of the quadder control devices.

According to the embodiment of the invention illustrated in the drawings, the vise frame 1, shown in outline in Figure 1, is formed with laterally extending brackets 2, 3 embracing a vertical cam shaft 4. The lower vise frame bracket 2 is supported on ball bearings in a member 5 forming part of the main frame of the machine, and the cam shaft 4 is supported in the said member 5 and by bearing brackets 6, 7 formed on or secured to a side member 8 of the main frame. The vise frame 1 is thus hinged to turn into and out of operative position about the vertical axis of the cam shaft 4; it may be secured in its operative position in the usual manner by locking members of known form indicated at 9 (Figure 1), or by other appropriate means, and it constitutes a self-contained unit comprising a line transporter, justifying mechanism and quadding mechanism, with operating devices therefor, as hereinafter described. The cam shaft 4 by which the said operating devices are controlled, is operatively connected to the main cam shaft 18, for example, by bevel gears 19, 20 and shaft 21, see particularly Figure 3. It will be understood that the cam shaft 18, in the present arrangement, is similar to the main cam shaft of known machines, and carries cams and gears arranged to control, in substantially the normal way, the operation of organs of the machine other than those controlled by the cam shaft 4.

The line transporter or elevator 10 (see Figure 1) is mounted in a slide 11 at the top of the vise frame 1, in which slide the elevator can be moved downwardly from the position shown in Figure 1, in which it receives a composed matrix line from which a slug is to be cast, to casting position in which the line is sustained between clamping jaws 12, 13, mounted in the vise frame 1. The movements of the elevator 10 are controlled by a cam 14 on the vertical shaft 4 through a lever 15 and a spring-loaded link 16. The lever 15 is fulcrumed on a bracket 17, the base of which surrounds the shaft 4 and is supported between the arms of the forked bracket 7, whereby the lever 15 and bracket 17 are enabled to participate in the movement of the vise frame 1.

pate in the pivotal movement of the vice frame 1. It should be noted that the elevator 10 moves downwardly under the action of gravity when such movement is permitted by rotation of the 5 cam 14, and is positively moved upwardly by the action of the cam 14 on the lever 15, to return it to the position shown in Figure 1, for the discharge of a line which has been cast and the reception of a succeeding line; the spring loading of the link 16 permits yielding in the event of the upward movement of the elevator being obstructed.

The justifying mechanism employed in carrying out the invention according to the present embodiment thereof, comprises, as is usual, a horizontal justification bar 22 carried by two vertical rods 23, 24 slidably in guides at opposite sides of the vise frame, which bar is adapted to engage the depending slides of spacebands in the 10 composed line when the latter is in casting position between the vise jaws 12, 13. In order to operate the justification rods 23, 24 under the control of a cam 25 on the shaft 4, the said rods are connected together at their lower ends by 15 a bar 26 which is acted upon by rollers 27, 28 on the two arms of a lever 29 fast on a rock shaft 30 extending across the vise frame 1. The left-hand end of the rock shaft 30 (as viewed in Figure 2) is extended through the vise frame and 20 has fast on it an arm 31 provided with a roller 32 held up to the face of the cam 25 by a spring 33 acting between said arm and the vise frame. The spring 33 effects the operative movement of the justification bar 22 through the connections 25 30 just described, and the cam 25 normally retains the bar in its inoperative position (as shown in Figure 2) against the action of the spring.

For the purpose of automatically quadding or centering a short line, it is preferred to employ 40 in conjunction with the present improved vise-frame, a modified form of the known type of quadding mechanism comprising a pair of levers 34, 35 (Figure 2) connected by links 36, 37 to the vise-jaw blocks 38, 39 respectively, and arranged 45 for connection to or disconnection from a vertically reciprocable rod by which the quadding movement of either or both of the jaws is effected. Such modified form, which permits the mechanism to be controlled by a cam 40 on the 50 shaft 4, and leaves the central portion of the vise frame 1 free from obstructions, will now be described.

According to the invention an operating rod is 55 provided for each of the levers 34, 35, a rod 41 being appropriate to the lever 34 connected with the left-hand vise jaw 12, and a rod 42 appropriate to the lever 35 connected with the right-hand vise jaw 13, said rods being disposed one at each side of the vise frame. The control rods 60 are slidably and rotatably mounted in guides 43, 44, and are connected together at their lower ends by a transverse bar 45 relatively to which the rods are free to rotate. The operative reciprocating movements of the rods 41, 42, are 65 transmitted thereto through the bar 45. For this purpose the bar 45 is connected by adjustable depending links 46 to arms 47 of a lever member freely mounted on a transverse rock shaft 48, which lever member carries a spring barrel 70 49 having a plunger 50 and is formed with a bridge-piece 51. The shaft 48 has fast to it a lever arm 52 extending forwardly between the bridge-piece 51 and the plunger 50, and a further arm 53 fast to its left-hand end, beyond the 75 vise frame, carrying a roller 54 in engagement

with the cam 40. An adjusting screw 55 in the bridge-piece 51 bears on the underside of the lever arm 52. These connections ensure that when the lever arm 53 is actuated by the cam 40 the arm 52 acts through the spring plunger 50 to move the control rods 41, 42 upwardly. By such upward movement the jaw-operating lever or levers for the time being connected to one or both of the rods, is or are actuated to close the respective jaw or both jaws inwardly into contact with the composed line.

To enable the control rods 41, 42 and jaw operating levers 34, 35, to be connected and disconnected as desired, the lower arm of each lever is provided with a projecting pin 56 adapted to 15 be engaged by a grooved collar 57 the lower flange of which is mutilated, at the upper end of each control rod. The angular dispositions of the mutilated portions of the collar flanges, as will be understood by reference to Figure 5, are 20 such that by simultaneous angular adjustment of the two rods, both levers may be disconnected for normal working (position A in Figure 5), or connected as shown at C for centering; the lever 34 only may be connected for quadding with 25 the left-hand jaw 12, which setting is indicated at B, or the lever 35 only may be connected for quadding with the right-hand jaw 13 as indicated at D in the said figure.

Angular adjustment of the rods is provided for, 30 in the arrangement shown, by axially fixed gears 58 splined to the rods in engagement with racks 59 connected to a manually operable setting lever 60. The racks 59 are carried, in relatively 35 offset relationship, on a slide 61 at the front of the vise frame, one of the racks being arranged to engage at the front the gear appropriate to the rod 41 and the other rack disposed at the rear of the gear appropriate to the rod 42, as shown best in Figure 4, so that transverse adjustment of the slide 61 effects angular movement of the gears in respectively opposite directions. A link 62 connects the slide 61 with the lever 60 and the latter may be provided with a detent device, such as a spring plunger 63 co-operating with holes in a plate 64 by which the 40 position of the rack mechanism may be determined for each of the settings, in accordance with indications "Reg.", "LH.", "C." and "RH." appearing on the plate 64 as shown in Figure 2. 45

With the above-described arrangements of the elevator, justifying mechanism and quadding mechanism, the central portion of the vise frame is left clear, thus providing a construction particularly suitable for use in a machine comprising 55 a mould which is movable from casting position to a horizontal ejecting position below the casting position. Moreover, the vise frame with the associated mechanisms may be turned outwardly about the axis of the cam shaft, while the cam levers remain in contact with their operating cams, to give complete freedom of access to the rear of the vise frame and to the machine parts located to the rear thereof when it is in its operative position.

It is to be understood that the constructional forms of the devices above-described are given merely as examples of one convenient arrangement of mechanism according to the invention, and that a vise frame according to the invention may embody devices of various constructions operable from a cam shaft about the axis of which the vise frame with its associated devices is adjustable as a self-contained unit.

Having described our invention, we declare that 75

what we claim and desire to secure by Letters Patent is:

1. In a typographical slug casting machine, the combination of a vise frame pivotally movable into and out of operative position, and a rotatable cam shaft co-axial with the pivot of the vise frame adapted to control the operation of mechanisms carried on said vise frame. 5
2. In a typographical slug casting machine, the combination of a vise frame pivotally adjustable into and out of operative position, cyclically operable mechanisms carried on said vise frame, rotatable cams mounted co-axially with the pivot of the vise frame, and levers adjustable with the vise frame operatively connecting said mechanisms and cams. 10
3. In a typographical slug casting machine, the combination of a vise frame pivotally adjustable into and out of operative position, a line transporter reciprocable on the vise frame, a cam and lever adapted to control the reciprocation of the transporter and a bracket on which said lever is fulcrumed, said cam and bracket being mounted for rotation about an axis aligned with the pivot 25 of the vise frame.
4. In a typographical slug casting machine, the combination of a vise frame pivotally adjustable into and out of operative position, two justification rods vertically slidable in guides at respectively opposite sides of the vise frame, a justification bar carried by said rods at their upper ends, an operating bar connecting the justification rods at their lower ends, a rock shaft extending across the vise frame parallel with said operating bar, a lever arm fast on said rock shaft intermediate its ends and extending beneath said operating bar, a cam rotatable about an axis aligned with the pivot of the vise frame, an arm fast on one end of said rock shaft and a spring 35 acting on the last-mentioned arm to hold it in contact with said cam.
5. In a typographical slug casting machine, the combination of a vise frame pivotally adjustable into and out of operative position, quadding 40 mechanism mounted on the vise frame, a cam rotatable about an axis aligned with the pivot of the vise frame and a system of levers mounted on the vise frame controlled by said cam adapted to operate said quadding mechanism.
6. In a typographical slug casting machine, the combination of a vise frame pivotally adjustable into and out of operative position, a pair of line-clamping jaws mounted on said vise frame, quadding mechanism mounted on said vise frame 45 comprising a vertically reciprocable rod appropriate to each such jaw, a lever appropriate to each jaw and rod, devices adjustable to connect and disconnect each lever to the respective rod, and a system of levers mounted on the vise frame 50 operable to reciprocate the rods, and a cam rotatable about an axis aligned with the pivot of the vise frame adapted to control the operation of said quadding mechanism.
7. In a typographical slug casting machine, the combination of a vise frame pivotally adjustable into and out of operative position, a pair of line-clamping jaws mounted on said vise frame, quadding mechanism mounted on said vise frame comprising a vertically reciprocable rod appropriate to each such jaw, a lever appropriate to each jaw and rod, devices adjustable to connect and disconnect each lever to the respective rod, means adapted to effect conjoint adjustment of 55 said devices and a system of levers mounted on the vise frame operable to reciprocate the rods, 60
8. In a typographical slug-casting machine, a combination according to claim 6 wherein the vertically reciprocable rods are located at respectively opposite sides of the vise frame. 65
9. In a typographical slug casting machine, the combination of a vise frame pivotally movable into and out of operative position, a rotatable cam shaft co-axial with the pivot of the vise frame adapted to control the operation of mechanisms carried on said vise frame, a main cam shaft and a driving connection from said main cam shaft to the first-mentioned cam shaft. 70
10. In a typographical slug casting machine, the combination of a vise frame pivotally adjustable into and out of operative position, a pair of line-clamping jaws mounted on said vise frame, quadding mechanism mounted on said vise frame 75 comprising a vertically reciprocable rod appropriate to each such jaw, a lever appropriate to each jaw and rod, a projecting pin on each lever, a grooved collar on each rod which in different angular positions is engaged with or disengaged from the respective pin, a setting device adapted to adjust angularly said collars simultaneously in respectively opposite directions and a system of levers mounted on the vise frame operable to reciprocate the rods, and a cam rotatable about an axis aligned with the pivot of the vise frame adapted to control the operation of said quadding mechanism. 80
11. In a typographical slug casting machine, the combination of a vise frame pivotally movable into and out of operative position, a rotatable drive shaft co-axial with the pivot of the vise frame adapted to control the operation of mechanisms carried on said vise frame, and operative connections between the drive shaft and said mechanisms. 85
12. In a typographical slug casting machine, the combination of a vise frame pivotally movable into and out of operative position, a rotatable drive shaft co-axial with the pivot of the vise frame adapted to control the operation of mechanisms carried on said vise frame, and operative connections between the drive shaft and said mechanisms adapted to be maintained during the movements of the vise frame. 90
13. In a typographical slug casting machine, the combination of a vise frame movable into and out of operative position, a justification bar supporting means therefor arranged to slide vertically in guides on the vise frame, means for effecting the vertical sliding movement of said supporting means, and operative connections between said supporting means and the means for effecting its movement adapted to be maintained during the movements of the vise frame. 95
14. In a typographical slug casting machine, the combination of a vise frame movable into and out of operative position, a justification bar, supporting means therefor arranged to slide vertically in guides located laterally of the center of the vise frame and connected together near their upper and lower ends only so as to leave the central portion of the vise frame unobstructed, means for effecting the vertical sliding movement of said supporting means, and operative connections between the lower end of said supporting means and the means for effecting its movement adapted to be maintained during the movements of the vise frame. 100
15. In a typographical slug casting machine, 75

- the combination of a vise frame pivotally movable into and out of operative position, a justification bar, a pair of supporting rods therefor vertically 5
slidable in guides at respectively opposite sides of the vise frame, means co-axial with the pivot of the vise frame for controlling the vertical sliding movement of the rods, and operative connections between the lower ends of the rods and the means for controlling their movement.
- 10 16. In a typographical slug casting machine, the combination of a vise frame pivotally movable into and out of operative position, a line transporter reciprocable in the vise frame, means co-axial with the pivot of the vise frame for effecting 10
the operation of the line transporter, and operative connections between the line transporter and its operating means adapted to be maintained during the movements of the vise frame.
- 15 17. In a typographical slug casting machine, 15
the combination of a vise frame pivotally movable into and out of operative position, quadding mechanism mounted in the vise frame, means co-axial with the pivot of the vise frame for effecting the operation of the quadding mechanism, and operative connections between the quadding mechanism and its operating means adapted to be maintained during the movements of the vise frame.
- 20 18. In a typographical slug casting machine, 20
the combination of a vise frame pivotally movable into and out of operative position, a line transporter mounted in the vise frame and reciprocable therein, justifying mechanism mounted in the vise frame, quadding mechanism mounted 25
in the vise frame, said line transporter, justifying mechanism and quadding mechanism being movable with the vise frame, a drive shaft co-axial with the pivot of the vise frame and common to said line transporter, justifying mechanism and quadding mechanism, means for actuating the drive shaft, and operative connections between the drive shaft and said line trans-
- porter, justifying mechanism and quadding mechanism adapted to be maintained during the movements of the vise frame.
- 25 19. In a typographical slug casting machine, 25
the combination of a vise frame, a pair of line-clamping jaws movably mounted in the vise frame, quadding mechanism mounted in the vise frame including a pair of vertically reciprocable rods associated one with each of said jaws, and means for actuating said rods to effect the movement of either or both of said jaws into and out of line-clamping position.
- 30 20. In a typographical slug casting machine, 30
the combination of a vise frame, a pair of line-clamping jaws movably mounted in the vise frame, quadding mechanism mounted in the vise frame including a pair of vertically reciprocable rods associated one with each of said jaws, means for selectively connecting either or both of said rods with their respective jaws, and means for actuating said rods to effect the movement of either or both of said jaws into and out of line-clamping position according as the jaws are selectively connected to the rods.
- 35 21. In a typographical slug casting machine, 35
the combination of a vise frame, a pair of line-clamping jaws movably mounted in the vise frame, quadding mechanism mounted in the vise frame including a pair of vertically reciprocable rods associated one with each of said jaws, means individual to the rods for establishing a connection between each rod and its respective jaw, common means for selectively effecting the connection of either or both of said rods with their respective jaws, and means for actuating said rods to effect the movement of either or both of said jaws into and out of line-clamping position according as the jaws are selectively connected to the rods.
